UNITED STATES PATENT OFFICE.

ORVILLE SIMPSON, OF COLLEGE HILL, OHIO.

GRINDING-MILL.

SPECIFICATION forming part of Letters Patent No. 423,704, dated March 18, 1890.

Application filed October 21, 1889. Serial No. 327,629. (No model.)

To all whom it may concern:

Be it known that I, ORVILLE SIMPSON, a citizen of the United States, residing at College Hill, in the county of Hamilton and State 5 of Ohio, have invented certain new and useful Improvements in Grinding-Mills, of which the following is a specification.

My invention relates to the class of grinding-mills in which the operating burrs or stones are mounted one above the other within a suitable frame, the running-burr being mounted on a vertical spindle, which is supported by a bridge-tree and pivotal lighter-bar and provided with regulating devices 15 whereby the said stones may be run a greater or less distance apart, as desired; and my invention consists in the construction and arrangement of safety devices, all as hereinafter fully described, and particularly pointed 20 out in the claims.

In the accompanying drawings, Figure 1 is a central sectional elevation of a grinding-mill with my present improvements (described and claimed herein) applied thereto, the curb 25 or casing usually around the burrs being omitted; Fig. 2, a vertical section, partly in elevation, of my improvements complete, showing the bridge-tree and lighter-bar broken off; Fig. 3, a transverse sectional elevation on line 30 $\alpha\alpha$, Fig. 2; and Fig. 4, a broken longitudinal elevation of the lighter-bar, showing its outer or free end, which engages my improved device.

A represents the uprights, and A' the connecting-girders or cross-beams, which together form the usual frame of an ordinary grinding-mill.

B represents the upper or stationary burr, and C the lower or running burr, of the mill 40 shown in the drawings. Both said burrs may be supported and incased in any desirable manner, the lower or running one being suitably mounted upon and connected with a tapered spindle or upright shaft D, so as to revolve 45 therewith, and said shaft being properly journaled at its upper and lower ends, as customary or desired.

$a\alpha$ are the customary bevel driving-gears, the driven one a' being keyed to spindle D, 50 and the driver a to the horizontal shaft b.

E represents the bridge-tree, supported at its ends by the girders A'; and F the lighter-

bar located directly under the bridge-tree, being pivotally connected at one end to the bottom thereof. The said horizontal shaft b is 55 journaled in the lighter-bar intermediate the ends of the latter, as clearly shown in Fig. 1 and as usual.

G represents a hollow post or stand-pipe mounted upon one end of the bridge-tree, and 60 c the usual regulating screw or rod for the adjustment of the running-stone. Said regulating-screw passes upward through an aperture or slot G' in the bridge-tree and the hollow of said post to receive a hand-wheel or 65 nut d on its upper screw-threaded end, and also an elastic rubber cushion or spring e, which latter fits loosely upon said screw intermediate the central hub of said hand-wheel and the top of said post.

c' is a loop or stirrup formed at the lower end of the regulating-screw c, and c'' represents the lower cross-bar or ligament of said stirrup, upon which the outer or free end of the lighter-bar has heretofore rested for support at all times, both while the burrs were running close together and thrown apart.

f is a notch in the lower edge of the said outer end of the lighter-bar.

H represents a transverse frangible pin, 80 whose ends fit within suitable openings made in the enlarged portions h of the vertical sides of stirrup c', slightly above the said cross-piece c'', and provided to support the notched free end of the lighter-bar, in the manner and 85 for the express purpose immediately herein-after described. The pin H is an auxiliary one in connection with said cross-piece c'', and is preferably made of wood of sufficient strength to normally bear the weight of the parts supported by the lighter-bar and to withstand the resistance or strain incident to the ordinary grinding of the mill on grain, but which immediately yields or breaks on the entrance of any hard foreign matter—such as stones, bolts, 95 nuts, or the like—between the burrs, thereby causing the running-stone to continue to rotate a suitable distance apart from its companion burr to permit the said foreign matter to escape or be removed from between said burrs, 100 thus preventing any further material injury to the grinding-surfaces of either of said burrs.

In the operation of my device the free end

of the lighter-bar drops instantly on the rupture of the auxiliary pin H and is at once caught by the cross-piece c'' of the stirrups c', its notch f engaging said cross-piece in the usual manner. The mill may continue to grind after the breaking of pin H by merely turning the hand-wheel to raise the regulating-screw and the lighter-bar, with the grinding devices, to their former positions, and the rubber cushion or spring e, above described, used to operate singly in connection with the burrs and permit them to part sufficiently for the escape of any foreign matter should an unusual strain, caused by any such resistless foreign matter, accidentally enter between them.

It is obvious that both the wooden pin H and elastic spring-cushion e can be used together in connection with the grinding devices, as herein shown and described, or they may be used or applied separately, as desired; but the former combination I deem the better, for the reason that should the pin break the mill need not necessarily be stopped to renew said pin, but it may go on grinding and the hand-wheel be turned so as to bring the running-burr into working position, the said elastic cushion e then presenting a sufficiently yielding bearing or support to permit the escape of foreign matter should any enter between the burrs, as previously stated herein. It is also obvious that instead of using a rubber cushion on the regulating-screw, as shown, a spiral spring could be substituted and the device operate quite as well.

I claim—

1. In a grinding-mill, the combination, with

the pivotal lighter-bar, vertical spindle, burrs B and C, and vertical regulating-screw c, the latter being passed upward through a cylinder or hollow post G and engaged by an adjusting hand-wheel d on its upper threaded end, of a transverse break-pin H, mounted in the stirrup or loop c' at the lower end of said regulating-screw, and cross-bar c'', forming the bottom of said stirrup, constructed, arranged, and adapted to operate substantially in the manner and for the purpose specified.

2. The regulating screw or rod c, having at its lower end a loop or stirrup c', cross-bar c'', forming the bottom of said stirrup, and transverse break-pin H, mounted in said stirrup parallel with and slightly above said cross-bar, substantially as and for the purpose specified.

3. In a grinding-mill, the combination of a pivotal lighter-bar, vertical spindle, burrs B and C, regulating-screw c, hand-wheel d, hollow post or cylinder G, loop or stirrup c' at lower end of said regulating-screw, transverse bar c'' of said stirrup, break-pin H, mounted in said stirrup slightly above said transverse bar c'', and cushion or spring e, mounted on the upper end of said regulating-screw intermediate the top of said hollow post and hand-wheel, substantially as and for the purpose specified.

In testimony of which invention I have hereunto set my hand.

ORVILLE SIMPSON.
